FOOD VALUE SCALE

Harold Lawrence King, Mount Vernon, N. Y.

Application October 24, 1957, Serial No. 48,229

Term of patent 14 years

(Cl. D52—10)

Figure 1 is a front perspective view of a food value scale showing my new design;

Figure 2 is a right side elevational view thereof;

Figure 3 is a plan view thereof;

Figure 4 is a rear elevational view thereof.

I claim:

The ornamental design for a food value scale, substantially as shown.
